BURGLAR ALARM

Oscar M. Nelson, Chicago, Ill.

Application December 29, 1938, Serial No. 248,320

4 Claims. (Cl. 116—90)

This invention relates to an improved burglar alarm for windows of the sliding sash type, adapted to be associated with an upper and lower sash and to be actuated by the movement of either sash.

More particularly, it is an aim of this invention to provide a wheel having its periphery in frictional engagement with the frame of one sash and supported by another sash whereby said wheel will be revolved by the movement of either sash, and means connecting said wheel to a gong to be actuated by the movement thereof to produce an audible alarm.

It is a further object of this invention to provide a burglar alarm of simple compact construction, which may be economically manufactured and which is adapted to be readily attached to conventional window sashes of conventional construction and to be actuated thereby without modification of the sash frames.

A particular advantage of the invention resides in the fact that due to its size it can be positioned on a window in such a manner as to be substantially invisible from the outer side of the window so that its existence would not be disclosed until the alarm had been sounded by the opening of the window.

Other objects and advantages of the invention will hereinafter become more fully apparent from the following description of the drawing, which illustrates a preferred embodiment thereof, and wherein:

Figure 1 is a top plan view of the invention shown associated with two window sash frames,

Figure 2 is a front elevational view of the same,

Figure 3 is a horizontal central sectional view of the invention, and

Figure 4 is a vertical sectional view taken on the line 4—4 of Figure 3.

Referring more particularly to the drawing, wherein like reference characters designate like or corresponding parts throughout the different views, 10 designates generally a portion of a top rail of a lower window sash frame and 11 a portion of the side rail of the upper window sash frame which are slidably mounted in the window frame 12 in the conventional manner.

The alarm, designated generally 13, includes a bell designated generally 14, and comprising the stationary section 15 which is preferably circular and provided with an outturned annular flange 16 the edge of which is adapted to be slightly spaced from the open edge of the gong section 17 of the bell to form with the section 15 the chamber 18. The general shape of the bell 14 is conventional

and may be modified without affecting the invention.

Bell section 15 is rigidly supported by means of the legs 19 which are secured to the outer side thereof and which are removably secured at their free ends by means of the fastenings 20 to the top rail 10. Section 15 is provided with a central threaded opening 21 in which is removably mounted the externally threaded sleeve 22, which has its ends projecting outwardly from the opposite sides of the section 15. Mounted on the threaded end of the sleeve 22 which is disposed on the outer side of the bell 14 is one end of a bracket 23. Bracket 22 is of hook shaped form with the wheel 24 journaled on its free end and disposed at right angles to the bell 14 and positioned so that the periphery 25 thereof is in frictional engagement with the side rail 11 of the upper sash. Wheel 24 on its outer side is provided with a beveled gear 26, formed integral 20 therewith and adapted to mesh with a smaller beveled gear 27.

The beveled gear 27 has a shaft 28 projecting therefrom which is journaled in the sleeve 22 and which extends therethrough. The free end of the shaft 28 is threaded to engage an internally threaded tip 29 which is formed on the inner side of the gong 17 to connect with beveled gear 27.

Gong 17 is provided with a plurality of indentations forming the inwardly extending projections 30. Secured to the inner end of the sleeve 22 and disposed in the chamber 18 of the bell 14, is a triangular shaped clapper 31 having a central opening 32 through which extends the shaft 28. The three corners of the clapper 31 are 35 rolled to form the hammers 33 which are disposed in the path of the projections 30 to be engaged thereby when the gong 17 moves relatively to the hammers 33.

From the foregoing it will be seen that when either the upper or the lower sash frame of the window is moved the rails 10 and 11 will be moved relatively to each other so that the wheel 24 will be revolved by the frictional engagement of its periphery 25 with the side rail 11 to thereby revolve the gear 27, shaft 28 and the gong 17 which is connected thereto. Gong 17 will be revolved relatively to the clapper 31 which is held stationary by the sleeve 22, to which it is attached, so that the projections 30 will strike the hammers 33 to cause the conventional audible ring of a gong.

The periphery 25 of the wheel 24 may be serrated for better engagement with the rail 11 or may be provided with a removable rubber 55

tread for better frictional engagement and to prevent marring of the rail 11.

Various other modifications and changes in the construction and arrangement of the parts forming the alarm may obviously be made and are contemplated.

I claim as my invention:

1. In a device of the class described, a bell including a stationary element and a gong, means for rigidly supporting said stationary element on the top of a lower sliding window frame sash, a sleeve extending through said stationary element and rigidly secured thereto, a bracket mounted at one end on said sleeve, a wheel journaled on the opposite end of said bracket for frictional engagement with the side rail of the upper sash, said wheel being provided with a beveled gear on one of its sides, a beveled bear having a shaft projecting therefrom and journaled in said sleeve, said gong having an internally threaded tip on its inner side for engagement with the threaded end of said shaft, and a clapper secured to one end of said sleeve and disposed within said bell for engagement with portions of said gong, said gears being enmeshed to revolve said gong when the window sashes are moved relatively to each other.
2. In a burglar alarm for windows, a supporting member mounted on the top rail of a lower window sash, a sleeve extending through said supporting member, a bracket supported by said sleeve, a wheel journaled on said bracket and having its periphery in frictional engagement with a side rail of an upper sash, said wheel

being provided with an integrally formed beveled gear, and a beveled gear for engagement with said first mentioned beveled gear provided with a shaft journaled in said sleeve, a gong secured to the free end of said shaft to be revolved by the movement of said gears, and a clapper connected to said sleeve for engagement with said gong.

3. A device as in claim 2, said clapper being triangular in shape and provided with enlarged portions at its corners forming hammers, and said gong being indented to provide inwardly projecting elements for engagement with said hammers.

4. An alarm comprising a wheel having its periphery in frictional engagement with a side rail of a window sash, means for supporting and journaling said wheel, said wheel being provided with an integrally formed beveled gear on one of its sides, a beveled gear enmeshed with said first mentioned gear, a shaft secured to and projecting from said last mentioned beveled gear, means for supporting and journaling said shaft, said last mentioned means being mounted on a window sash frame, a gong mounted on the free end of said shaft to be revolved by the operation of said gears, said gong having a plurality of spaced indentations, and a fixed clapper supported by said last mentioned means and provided with a plurality of hammers projecting into said gong for engaging said indentations when the gong is revolved.

OSCAR M. NELSON.
